FIG. 2

FIG. 3

FIG. 4

FIG. 8

FIG. 5

FIG. 6

FIG. 7

FIG. 1 is a right side isometric view of a building embodying my design, the view being taken from an elevation higher than the roof ridges;

FIG. 2 is a central longitudinal sectional view through the building, as indicated by the line 2—2 of FIG. 3;

FIG. 3 is a top plan view of the same building;

FIG. 4 is a right side elevation of the same;

FIG. 5 is a left side elevation of the same;

FIG. 6 is a front elevation of the same;

FIG. 7 is a rear elevation of the same; and

FIG. 8 is a fragmentary vertical sectional view through

a portion of one of the overhanging canopies, all four of which are clearly shown in FIG. 3. This view is taken along the line 8—8 of FIG. 3.

I claim:

The ornamental design for a building, substantially as shown.
